9117

UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,890, dated March 18, 1884.

Application filed February 13, 1884. Term of patent 3½ years.

To all whom it may concern:

Be it known that I, JOHN QUINCY REED, of the city, county, and State of New York, have invented and produced a new and original Design for a Pattern of a Lady's Costume, (numbered 9,417;) and I do hereby declare that the engraved prints accompanying this specification convey to any one accustomed to using paper patterns a clear understanding of how a garment made up by the pattern will appear.

The design shows a round walking-skirt and a round waist. The skirt displays a pointed drapery crossing the front and right side, and exhibiting draping plaits in its side edges, a deep panel at the left side, and a full deep back drapery displaying draping plaits in its

front edges, and falling to a greater depth at the right side than at the left. The waist exhibits a smoothly-fitting yoke at the front and back, a full body-front, and a full body-back displaying frilled upper edges, and a belt at the lower edges, coat sleeves, and a standing collar.

What I claim as my invention, and desire to secure by Letters Patent, is—

The design for a lady's costume, as shown in the engraved prints accompanying this specification.

JOHN QUINCY REED.
